UNITED STATES PATENT OFFICE.

KARL BYINGTON, OF CHICAGO, ILLINOIS.

DESIGN FOR A SAVINGS AND DISCOUNT CHECK.

51,093.

Specification for Design.

Patented July 31, 1917.

Application filed February 5, 1917. Serial No. 146,619. Term of patent 3½ years.

To all whom it may concern:

Be it known that I, KARL BYINGTON, a citizen of the United States, residing at Chicago, in the county of Cook and State of Illinois, have invented a new, original, and ornamental Design for Savings and Discount Checks, of which the following is a specification, reference being had to the accompanying drawing, forming part thereof.

The figure is a front elevation of a savings and discount check illustrating my new design.

I claim:

The ornamental design for a savings and discount check, as shown.

KARL BYINGTON.
